ATTORNEY'S

UNITED STATES PATENT OFFICE.

HENRY LUTZ, OF LOGAN, OHIO.

CAR-STEP.

SPECIFICATION forming part of Letters Patent No. 462,496, dated November 3, 1891.

Application filed May 15, 1891. Serial No. 392,806. (No model.)

To all whom it may concern:

Be it known that I, HENRY LUTZ, a citizen of the United States, residing at Logan, in the county of Hocking and State of Ohio, have 5 invented a certain new and useful Improvement in Railway-Car Steps, of which the following is a specification.

My invention relates to the improvement of extension-steps for railway-cars; and the 10 objects of my invention are to provide simple and improved means for extending the lower step of a series of car-steps, to provide in connection therewith means for quickly and conveniently elevating said lower step against 15 the under side of the step-frame when not in use, and to produce other improvements in the details of construction, which will be more fully pointed out hereinafter. These objects I accomplish in the manner illustrated in the 20 accompanying drawings, in which—

Figure 1 is a side elevation of a set of car-steps, showing, for the sake of clearness, a portion of the siding broken away therefrom, showing in full lines the position of my extension mechanism when the lower step is elevated and in dotted lines the position thereof when the same is lowered or extended. Fig. 2 is a plan view of that side of the stairway upon which is mounted my hand-operating 25 device, showing the latter in cross-section. Fig. 3 is a central vertical section enlarged from Fig. 1 of said hand-operating device. Fig. 4 is a rear view of the stairway provided with my improvements and showing the lower 30 step extended. Fig. 5 is a view showing a modification in the manner of operating my device, and Fig. 6 is a detail view of one of the parts employed in said modification.

Similar letters refer to similar parts throughout the several views.

a represents a portion of one of the end platforms of a car, and a' the outward extensions thereof, which extend on opposite sides of the usual stairway-recesses.

b represents the ordinary form of stairway, which is inclined outwardly and downwardly from the platform a in the usual manner. Of this stairway b represents the side pieces, b' the fixed steps, which are arranged at intervals between said side pieces, and b'' the step backing-pieces, which ordinarily cover the rear sides of the steps. Upon the upper side

of the platform a, on one side of the stairway and near the rear side of the latter, is fixed a metallic plate b³, from which rises a vertical 55 and fixed tube b¹. This tube b¹ has telescoped therein a tube b⁵, the upper and smaller end portion of which is internally screw-threaded, as shown.

c represents a lever-operating or plunger 60 rod, which passes loosely through the tubes b⁴b⁵. This rod c has its upper end screwed within the upper end portion of the tube b⁵, and the latter is provided with an upward extension and finger-piece c'. The lower 65 portion of the rod passes, as shown, through the lower open end of the tube b⁴ and through an opening in the plate b³ and platform a beneath said tube. That portion of the rod c which is within the tubes b⁴b⁵ is, as 70 shown, provided with a coiled spring c², which surrounds the same, the upper end of said spring being fixed to the rod c or made to bear against the internal shoulders c³, formed by the production of the smaller neck or upper 75 end portion of the upper tube b⁵. The lower end of this spring is preferably caught, as shown, beneath the plate b³ and platform a. As shown in the drawings, the tube b⁴ is provided on one side adjoining its base-plate 80 b³ with an opening c⁴.

A notch or recess c⁵, designed to communicate with the case-opening c⁴, is formed in the rod c, said notch being so located that when said rod is drawn upward to its highest point, as hereinafter described, its notch will form an inward termination of the case-opening c⁴. Upon the plate b³ is fulcrumed at d a pawl or dog d', against one side of the outer portion of which is secured the end 90 of a spring-strip d², the free end of which bears against a pin d³, which projects upwardly from said plate b³. The pawl d' is so located with relation to the spring stoppin d³ as to cause through the tension of said 95 spring-strip an inward pressure on the outer portion of the pawl d', which will result in the inner end of the head of said pawl being held by spring-pressure within the opening c⁴ of the tube b⁴ and against the rod c on the 100 inner side of said tube. The lower end of the rod c, which extends through and beneath the platform a, is pivotally connected with the upper end of an approximately hook-

shaped lever-coupling d^4 , the lower hook end of the latter being pivoted or fulcrumed to one end of a downwardly-extending arm d^5 , the remaining end of which is rigidly connected with the outer end of a horizontal shaft d^6 , which extends inwardly at right angles with the arm d^5 through a rearward extension of one of the side pieces b , in which the outer end of said shaft bears. The inner 5 termination of the shaft d^6 is at the center of the width of the backing-piece b^2 , near which it is provided with a suitable bearing-box e , which projects from said backing-piece. Fixed on the inner end of the shaft d^6 is an 10 arm e' , to the outer or lower end of which is fulcrumed the upper end or stem of a bifurcated arm e^2 . The lower outwardly and thence downwardly extending forks of this arm e^2 are each pivotally connected with the upper 15 end of a downwardly-extending rod e^3 , said rods e^3 being supported loosely in suitable bearings or keepers e^4 , which project from the rear side of the step backing-piece. The rods e^3 are of such length that when forced 20 downward, as hereinafter described and as shown in Fig. 4 of the drawings, their lower forwardly-bent ends will be supported at a point beneath and in front of the lower fixed step of the stairway. Upon this forwardly-bent lower end portion of the rods e^3 is rigidly supported a lower or extension step f , which is of such length as to fit loosely when 25 so supported between the lower end portions of the stairway side pieces and beneath the lower fixed step.

The operation of my device is as follows: When the tube b^5 is down or inclosed by the tube b^4 , it will be observed that the spring-actuated rod c will have been forced downward to such an extent beneath the platform a as to result, through the connection of said rod and arm d^5 and the connection of the latter with the shaft d^6 , in the shaft-arm e' being made to extend outwardly from the step-backing. This position of the arm e' , owing 45 to its connection with the arm e^2 , results in the outward projection of the latter. This position of the arm e' results in the step-supporting rods e^3 being supported at such height 50 as to bring the step f into contact with the under side of the lowest fixed step b' .

The parts above described, and shown in Fig. 1 of the drawings, are normally supported in the positions described by the tension of 55 the coiled spring which is within the tubular portions b^5 b^4 . With the extension-step support in the elevated position described it is obvious that said step will be free from contact of platforms or other obstacles which 60 may be built adjacent to the railway. When the train has reached a station and it is desired to increase the length of the stairway for the accommodation of parties entering the train, the tube b^5 is pulled upwardly by 65 grasping the finger-piece c' and elevating the same until the notch c^5 of the rod c is opposite the recess c^4 in the tube b^4 , when the head

of the pawl d will, by pressure of the spring-strip d^2 , be caused to enter and engage with said notch c^5 , thus providing a support for 70 said rod and inner tube in their elevated positions. This upward movement of the rod c will result through the connection therewith of the arm d^5 in the outer end of the latter moving in the arc of a circle to the position 75 shown in dotted lines in Fig. 1, and the consequent inward straightening movement of the arms e' e^2 will result in a downward movement of the step-supporting rods e^3 and a consequent downward movement of the step f . 80 Owing to the fact that the rods e^3 travel in the direction of the incline of the stairway, it is obvious that the lower step f will be thus supported in proper alignment with the remaining fixed steps b' . In this manner the 85 stairway is extended the desired distance by a direct downward movement thereof. As the train is again started the brakeman or other employé may cause the extension-step to resume its elevated position by such pressure against the outer end portion of the pawl 90 d' as will result in the disengagement of the pawl-head with the notch c^5 of the rod c .

As shown in Figs. 5 and 6 of the drawings, I may elevate the tube b^5 through the pressure of the air from the air-brake pipes. This 95 means of operation is accomplished by supporting adjacent to the tube b^4 a tube i , which communicates at its lower end with an air-pipe i^2 , and within which is adapted to slide 100 a piston or plunger i^3 . The upper outwardly-projecting end of the piston i^3 may be connected with the upper end portion of the tube b^5 by means of a suitable arm i^4 , which couples said parts together. It will be readily understood that in this method of operation the air 105 from the air-brake pipes enters the tube i through the pipe i^2 and forces upward the piston i^3 , which in turn elevates the tube b^5 through the connecting-arm i^4 . 110

From the construction herein shown and described it will be seen that a simple and positive construction and arrangement of parts is produced, by means of which the extension-step may readily be returned from its 115 lowered position, and by means of which a convenient railway-stairway is produced.

Owing to the fact that the extension-step when not lowered is covered by the lower fixed step of the stairway, it will be seen that said extension-step will be free from the action of 120 snow or rain, and that its operating parts are protected from the weather by the platform and stairway backing.

I am aware that railway-car stairways or 125 steps have been produced heretofore with an extension-step; but my invention differs from these both in the manner of construction and operation.

Having now fully described my invention, 130 what I claim, and desire to secure by Letters Patent, is—

In steps for railway-cars, the combination, with the fixed steps and their supporting

frame-work, of the upwardly-extending tube b^4 , supported from the car-platform, telescoping tube b^5 , internal spring-actuated rod c^2 within said tubes and connected with tube b^5 , recess c^4 , and notch c^5 , formed, respectively, in the rod, tube b^4 , and rod c , as described, shaft d^6 , journaled at the back of the fixed steps, pivoted coupling-piece d^4 , connecting, as described, said shaft and rod c , shaft-arm e' , arm e^2 , jointedly connected therewith, step-

supporting rods e^3 , movably supported at the back of the steps b' , and a step supported on the lower ends thereof, said rods e^3 being jointedly connected with arm e^2 , substantially as described.

HENRY LUTZ.

In presence of—
I. C. WRIGHT,
WM. F. EISELE.
